UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK

SHADE-HOLDER.

1,379,066.

Specification of Letters Patent. Patented May 24, 1921.

Application filed January 14, 1920. Serial No. 351,478.

To all whom it may concern:

Be it known that I, ERNEST CANTELO WHITE, a citizen of the United States, residing in the borough of the Bronx of the city 5 of New York, in the State of New York, have invented certain new and useful Improvements in Shade-Holders, of which the following is a specification, reference being had to the accompanying drawings, forming 10 a part hereof.

The object of the present invention is to provide an improved shade holder which shall have universality of attachment to all 15 of the common types of electric sockets for supporting shades and reflectors. The types of shell sockets now commonly employed are brass shell sockets, the lower end having a small bead, and porcelain shell sockets having a groove near the lower end. There are 20 now used several forms of shade holders made for attachment to the brass shell sockets, but such holders cannot be attached to porcelain sockets and, conversely, the types of holders which are applicable to 25 porcelain sockets cannot be adapted to brass sockets, or if so attached support the shade or reflector out of proper alignment with the light source or eccentrically thereto. Further, such known holders are most difficult, 30 of manipulation in attaching to the shell socket and in attaching the shade or reflector thereto and often cause injury or permanent distortion of the shell.

The improved holder, when attached to a 35 shell socket, provides a firm grip with a maximum and uniform surface contact thereby eliminating such stresses on the shell as would tend to distort or break the same. It also provides a universality of application to shell sockets of all known types 40 and insures a ready and concentric adjustment under all conditions of use. It further provides a shade holder which is of simple construction and neat in appearance.

Another object of the invention is to provide an improved adjustable support for reflectors, such as are particularly adapted for 45 show windows and the like and in which it is desired to change the angular relation of 50 the reflector to the axis of the light.

In accordance with the first named object of the invention, there is provided a relatively flexible shell to which the shade or reflector may be readily attached and within 55 which is carried a flexible ring adapted to be

distorted to eccentric form to engage firmly the outer surface of a shell socket.

In accordance with the second named object of the invention, two types are illustrated, in one of which the flexible shell is held in a horizontal position or at any desired angle thereto by means of suitable adjustable devices which coöperate with the flexible ring and with the shell to hold the two in fixed relation, and in the other of which the shade holder is relatively fixed, but is provided with a plurality of depending arms to engage the shade or reflector, at least one of such arms being adjustable to permit ready engagement and disengagement of the shade or reflector with the arms and to permit the angularity of the reflector with respect to the axis of the lamp to be varied for windows of different heights, depths or other proportions.

The invention will be described with greater particularity hereinafter with reference to the accompanying drawings, in which—

Figure 1 is a fragmentary view in section through a shade and the improved shade holder and showing particularly the relation thereof to the shell socket and bulb.

Fig. 2 is a view, partly in horizontal section and partly in plan, of the improved shade holder and taken along the plane indicated by the line 2—2 of Fig. 1 and looking in the direction of the arrows.

Fig. 3 is a fragmentary view in section of a somewhat modified form of the shade holder, showing the parts constructed for attaching it to shades of different size.

Fig. 4 is a fragmentary detail view showing the relation of one of the adjusting screws to the flexible ring.

Fig. 5 is a view in vertical section of a window reflector and the improved shade holder showing the application thereto of the improved support for the reflector.

Fig. 6 is a view partly in plan and partly in horizontal section of the holder shown in Fig. 5 and taken along the plane indicated by the line 6—6 and looking in the direction of the arrows.

Fig. 7 is a detail view in perspective of a fragment of the adjustable arm shown in Fig. 5.

Fig. 8 is a detail view showing the relation of the adjusting screw to the adjustable arm of Fig. 5.

Fig. 9 is a view in vertical section of a window reflector and the improved shade holder, the shell being angularly adjustable to vary the angular relation of the reflector to the axis of the lamp.

Fig. 10 is a view in transverse section through the lamp socket shown in Fig. 9 and taken along the plane indicated by the line 10—10 and looking in the direction of the arrows.

While it will be appreciated as the description proceeds that one of the most important features of the invention resides in the universality of adjustment of the improved shade holders to sockets of varying types and dimensions, there is illustrated in Fig. 1, by way of example, a porcelain shell socket *a* having adjacent its lower end an annular groove *a'*. The shade holder comprises generally a relatively inflexible shell *b*, of annular form carrying thumb screws *c* at suitable points for engagement with the usual heel or lip *d* at the upper edge of the shade *d'*. The engagement and disengagement of the shade *d'* with the shell *b* through the thumb screws *c* will be effected in the manner commonly employed. Passing loosely through holes *b'* at another section of the shell *b* are two diametrically aligned screws *e* having enlarged heads *e'* adapted to bear in the extreme inner position of the screws against the surface of the shell. These screws are in threaded engagement with a flexible ring *f*, and one suitable method of effecting the engagement between the ring and the screw is illustrated in detail in Fig. 4. As there shown the ring *f* carries therein a threaded bushing *g* through which the screw *e* passes and the inner end of the screw may be offset, as at *e''*, to prevent its complete withdrawal from the bushing. The ring *f* is of such diameter as to clear freely the enlarged lower end *a''* of the shell socket *a* which would correspond, in the case of a metal socket, to the usual bead or external thread thereon.

The method of applying the shade holder readily to a shell socket, such as *a*, will be apparent. Whether or not the shade *d'* is first attached to the shell *b* of the holder, the screws *e* are threaded inwardly until the ring *f* assumes approximately its normal circular set. The holder is then passed over the shell socket *a* until the ring *f* is in alignment with the groove *a'*, or in the case of a metal socket, is above such bead as will correspond to the annular enlargement *a''* on the shell. By setting up on the screws *e* the flexible ring *f* is distorted and assumes the generally elliptical form illustrated in Fig. 2, the sides thereof along the minor axis being drawn into firm engagement with the surface of the shell socket at the bottom of the groove *a'*, and the sides along the major

axis being preferably limited in their distortion by relatively inflexible concentric shoes *f'* secured to the inner face of the ring. The surface contact afforded between the ring *f* and the shell socket is of very substantial area so that a very secure gripping is effected. This uniform and firm surface contact is of such substantial area as to prevent the imposition of undue stresses on the shell socket *a* such as would tend to distort or break the same. The weight of the shade *d'* is borne at such engaging surfaces and the security of the whole enhanced to a degree by the engagement of the shell and the enlargement *a''* with the lower edge of the ring *f*.

The shell *b* will tend to rock about the axis of the diametrically opposed screws *e* and advantage is taken of that condition, in accordance with another object of the invention, to provide a ready angular adjustment of the reflector *d'* with relation to the axis of the lamp in order to throw the light where it will be most useful. Devices are provided for locking the ring adjustably in fixed relation to the shell *b*. Suitable means for this purpose may comprise one or more studs *f''* secured to the ring *f* along an axis substantially at right angles to the axis of the screws *e* which stud or studs by manual distortion of the ring may be passed through any one of several holes *f'''* in the shell, during assembling, to give the desired angular relation between the reflector *d'* carried with the shell and the vertical axis of the lamp.

As illustrated in Fig. 3, the relatively inflexible shell *B* of the improved holder might be readily constructed so as to accommodate shades of much larger diameter. In this case there is provided a shouldered flange *B'* of much greater diameter than the body portion *B* and this shouldered flange *B'* will carry therein a plurality of thumb screws *G* for engagement with the larger shade. In this manner, the standardization of the holder for application to shell sockets of usual dimensions may be accomplished while provision is made for attachment of shades or reflectors of varying sizes.

Another embodiment of the invention is illustrated in Fig. 5 in its association with a form of the improved shade holder showing a special adaptation for supporting a glass show window reflector made without the usual heel or lip for engagement with the shade holder. Broadly considered, this support comprises a plurality of depending arms adapted to be inserted through the upper opening in the reflector, at least one of which is adjustable for the purpose of facilitating the engagement and disengagement of the arms with the reflector and the adjustment of the angularity of the reflector so

that the light is focused properly for windows of different heights, depths or other proportions.

The window reflector h , which is of any suitable form and dimensions for the purpose, has its upper edge h' unbroken in the sense that there is not provided the usual heel or lip for engagement with supporting devices. The shade holder i which may be 10 of the form previously described has secured to its inner surface two depending arms k which are relatively rigid and which are flanged at their lower ends, as at k' , to engage the inner face of the reflector at 15 points adjacent its upper edge h' . In the illustrated embodiment, the third supporting arm l is adjustably carried by the holder i through the medium of a screw m which passes loosely through an opening in the 20 wall of the holder i and may be threaded in a bushing m' secured in the arm l in much the manner described in connection with the construction shown in Fig. 4. The head m^2 of the screw m is exposed to facilitate 25 adjustment of the arm l in a manner to be described. The inner end of the screw m may be upset, as indicated at m^3 , to prevent its complete retraction from the bushing m' . The upper end of the arm l may 30 be confined by extending loosely through a slot i' formed in the upper wall of the holder i , the effect being somewhat that of a hinged joint whereby free movement of the lower end of the arm l is permitted. At 35 the lower end of the arm l may be stamped out three spaced lugs l' , l^2 , l^3 , on any one of which the upper edge h' of the reflector may rest. For the convenience of the window trimmer each of these lugs may be 40 stamped with a suitable legend indicating the proper lug for the support of the reflector depending upon the proportions of the window to be lighted.

In the use of the improved support the 45 screw m may be backed out to permit movement of the arm l to such a position as will enable the trimmer to pass the three arms k , l through the upper opening in the reflector h . The flanges k' of the relatively 50 rigid arms k will then be engaged with the inner wall of the reflector h and the proper one of the three lugs l' , l^2 , l^3 will be drawn into engagement with the reflector by setting up on the screw m . When the window 55 is relatively deep it will obviously be desirable to throw the light rearwardly to a greater extent than if the window be shallow and to attain this end the reflector h will be inclined at a substantial angle with 60 respect to the axis of the light source n . In this case, the rearmost portion of the reflector h will be tilted upwardly by engaging the uppermost lug l' on the arm l with the reflector. For windows of medium 65 depth it will be desirable to decrease the

angular relation between the reflector and the light source n , and in such case the second lug l^2 will be used for the support of the rearmost portion of the reflector, as indicated in Fig. 5. For shallow windows 70 where the light is to be focused more directly downwardly the lowermost lug l^3 is used as the support. By providing an adjustable arm, such as l , and properly graduating the lugs l' , l^2 , l^3 for windows of different dimensions, the personal factor is discounted and the trimmer will select the appropriate lug according to the directions. 75

A further feature of the invention which is important in fixtures used for window 80 lighting where the space is cramped resides in the accessibility of all of the parts which must be manipulated. The thumb screws o which are employed for drawing the flexible band o' into firm surface contact with the 85 shell socket p will be placed on an axis extending substantially at right angles to the axis of the screw m and in a plane parallel to the window pane so that the holder may be readily attached to the shell socket. The 90 screw m will be placed in the holder i at the side remote from the window pane so as to be readily accessible to the window trimmer. These advantages result from the peculiar character of the improved devices 95 and become of considerable practical importance in the art. In this form of shade holder a stud o^2 is shown on the ring o' for engagement with the shell i , it being contemplated that the shell shall be fixed in a 100 horizontal position while the reflector shall be adjusted angularly in the manner described.

The holder shown in Figs. 9 and 10 may be substantially like that shown in Fig. 1 105 including a relatively inflexible shell p^5 , a flexible band p' carried therein and adapted to be drawn into engagement with the shell socket by means of diametrically opposed screws p^2 , said flexible ring carrying diametrically opposed studs p^3 which may be 110 engaged with any one of a series of holes p^4 formed in the shell at opposite sides thereof and in the same vertical plane with the studs p^3 . When the studs p^3 rest in one set of 115 holes p^4 , as shown in Fig. 9, the shell will be held in a horizontal position. If the studs p^3 are retracted from that set of holes and the shell p^5 tilted about the screws p^2 in one direction or the other, the studs will 120 be engaged with another set of holes for the purpose of fixing the shell in such angular position. Hinged to the shell p^5 are a series of pendant arms q which may, conveniently, be four in number and arranged 125 in pairs at diametrically opposite points. The lower ends of these arms are hooked as at q' to engage the inner surface of a reflector r which may be formed without a lip or heel at its upper edge. Slidably 130

mounted on the arms q is a clamping ring s provided with holes s' therein through which the arms extend loosely, respectively, and preferably formed with a flange s^2 to 5 overlie the outer surface of the reflector r when the clamping ring is in position. The ring s has a central opening s^3 therein to receive the lamp t .

- The adjustment of the angular relation of 10 the reflector r with relation to the axis of the lamp t is secured in this embodiment in somewhat different manner than in the embodiment shown in Fig. 1 in which the reflector d' is fixedly secured to the shell. In 15 adjusting the angular relation of the reflector d' shown in Fig. 1 with relation to the axis of the lamp the reflector will swing about the screws e as a center. In adjusting the angularity of the reflector r shown in 20 Fig. 9 the reflector will swing about its own center of gravity in assuming an angular position with relation to the axis of the lamp. In effecting the adjustment, assuming that the arms q' are disengaged from the reflector 25 r the shell p will be locked in the horizontal or in the desired angular position to give the resulting inclination of the reflector r for the most useful reflection of light depending upon the character of the window. For instance, when the shell p is in a horizontal 30 position, as shown in Fig. 9, the ring s may be slid upwardly along the arms q' to move the lower ends of these arms inwardly, the diametrical distance between the holes s' 35 in the ring being less than the diameter of the shell p , whereby the arms q' are inclined downwardly and inwardly at all times. The result is that when the ring s is moved upwardly along said arms the latter have their 40 lower ends moved toward one another. The reflector r will then be moved into position to receive the ends of the arms q' through its upper opening and the clamping ring s then moved downwardly to throw the lower 45 end of said arms outwardly and into engagement with the inner surface of the reflector as shown in Fig. 9. The final movement of the clamping ring s to bring the flange s^2 into engagement with the outer surface 50 of the reflector r serves to clamp all of the arms q' in fixed engagement with the reflector r so that the latter is securely held in place. The illustrated embodiment has shown a reflector of such form that when the 55 shell p^5 is fixed in horizontal position the reflector will throw the light somewhat rearwardly of the vertical axis of the lamp as would be desirable in display windows of medium depth. In this case, one of the 60 pendant arms q^2 may be shorter than its opposite arm. When the shell p^5 is tilted up and the studs p^3 enter into holes in the shell along the line indicated at $t-t$, the arm q^2 will be lowered while its opposite arm will 65 be raised and the reflector r will swing about

its center of gravity to throw the light more directly downwardly, as would be desirable in a shallow window. When the shell p^5 is tilted in the opposite direction about the screws p^2 through the studs p^3 along the line indicated at $u-u$, the arm q^2 will be raised to the position indicated in dotted lines and its opposite arm will be lowered correspondingly and the reflector r will swing about its center of gravity into such a position as is indicated by dotted lines, thereby throwing the light well to the rear as would be desirable in a deep window. The openings s' in the clamping ring s through which the various arms q, q^2 extend are of such size as to 70 permit the clamping ring to conform to the tilting of the reflector r while being movable into such relation to the upper edge of the reflector and the arms as to lock the latter in engagement with the reflector. 75

While the improved support for window reflectors has been shown in association with the improved shade holder and while many advantages result from the adaptation of one to the other, it is to be understood, as is 80 evident from the different embodiments illustrated, that one may be used to advantage without the other. It will also be appreciated that changes in details of construction will suggest themselves to skilled mechanics, 85 but all such departures involving expediency only are to be deemed within the scope of the invention provided the desired results are obtained from devices which employ the principles described. 90

I claim as my invention:

1. A shade holder comprising a carrier, a relatively flexible ring supported within the carrier, and a means to elongate the ring for engagement along its minor axis with the 105 shell socket.

2. A shade holder comprising a relatively inflexible carrier having means to engage the shade, a relatively flexible ring supported within the carrier and means carried 110 on the carrier for elongating the ring for engagement along its minor axis with the shell socket.

3. A shade holder comprising a relatively inflexible carrier, a relatively flexible ring supported within the carrier and screws threaded in one of said members and co-operating with the other of said members to elongate the ring for engagement along its minor axis with a shell socket. 115

4. A shade holder comprising a carrier, a relatively flexible ring supported within the carrier, and screws threaded into the ring at diametrically opposite points and co-operating with the carrier to elongate the 125 ring for engagement along its minor axis with a shell socket.

5. A shade holder comprising an annular carrier having means to engage the shade, a flexible ring within the carrier, threaded 130

bushings in the ring at diametrically opposite points, and headed screws threaded into the bushings and extending loosely through the wall of the carrier, the heads of the 5 screws coöperating with the carrier to draw the ring into engagement with a shell socket.

6. A shade holder comprising a carrier made of a single piece of metal, a relatively flexible ring member supported within the 10 carrier, means to elongate the ring for engagement along its minor axis with a shell socket and studs secured to the ring along an axis substantially at right angles to the major axis of the ring for adjusting the angular relation of the carrier with respect to 15 the ring.

7. A shade holder comprising a relatively inflexible carrier having means to engage the shade, a relatively flexible ring supported 20 within the carrier, means carried on the carrier for drawing the ring into engagement with a shell socket and means to cooperate with the carrier and with the ring to adjust the angular relation of the carrier to the 25 ring.

8. A shade holder comprising a relatively inflexible carrier having means to engage the shade, a relatively flexible ring supported 30 within the carrier, means carried on the carrier for drawing the ring into engagement with the shell socket and means carried on the ring and engageable with the carrier to fix the latter in any desired angular relation to the ring.

35. 9. A shade holder comprising a relatively inflexible carrier having means to engage the shade and formed with a series of holes, a relatively flexible ring supported pivotally on the carrier at diametrically opposite 40 points, a stud carried on the ring substantially midway between said pivotal points and adapted to enter any one of said holes in the carrier, and means carried on the carrier for drawing the ring into engagement with a shell socket.

10. A shade holder comprising a carrier, a relatively flexible ring supported within the carrier, screws threaded into the ring at diametrically opposite points and coöperating 50 with the carrier to draw the ring into engagement with a shell socket, studs secured

to the ring at diametrically opposite points substantially at midway between said screws, said carrier being formed with a series of holes disposed in the same vertical 55 plane with said studs and adapted to be entered by said studs to lock the carrier in angular relation with the ring.

11. A shade holder comprising a carrier, means to secure the carrier to a shell socket 60 in any angular relation to the horizontal, a plurality of depending supporting arms carried by the carrier for engagement with a shade and clamping means coöperating with said arms to lock the same releasably in engagement with a shade.

12. A shade holder comprising a carrier, means to lock the carrier on a shell socket in any desired angular relation to the horizontal, a plurality of depending arms hingedly 70 secured to the carrier and a clamping member carried on said arms and coöperating therewith to lock the arms in engagement releasably with a shade.

13. A shade holder having a carrier, means 75 to lock the carrier on a shell socket in any desired angular relation to the horizontal, a plurality of depending arms hingedly supported on the carrier, a clamping ring through which said arms extend loosely, 80 said clamping ring serving to draw the lower ends of said arms inwardly and operable when moved downwardly on said arms to lock the same in engagement with a shade and when moved upwardly along said 85 arms to release them from engagement with a shade.

14. In combination, a shade holder comprising a carrier, a relatively flexible ring carried thereby, means to draw the ring into 90 engagement with a shell socket, means coöperating with the ring and the carrier to lock the carrier adjustably in any desired angular relation to the horizontal, a plurality of depending arms carried on the carrier 95 and a clamping member coöperating with said arms to lock the same releasably in engagement with a shade.

This specification signed this 12th day of January, A. D. 1920.

ERNEST CANTELO WHITE.
